UNITED STATES PATENT OFFICE.

WILLIAM M. BRUCE, JR., OF SPRINGFIELD, OHIO.

MULTIPLEX TELEGRAPHY.

Application filed May 2, 1921. Serial No. 466,015.

To all whom it may concern:

Be it known that I, WILLIAM M. BRUCE, Jr., a citizen of the United States, residing at Springfield, in the county of Clark and State of Ohio, have invented certain new and useful Improvements in Multiplex Telegraphy, of which the following is a specification.

My invention relates to multiplex telegraphy and has for its object transmission of a plurality of telegraphic messages over a single circuit. In accomplishing the above results, I make use of high frequency currents or electro-magnetic waves preferably in low frequency groups in connection with apparatus electrically tuned to the high frequencies and mechanically tuned to the low frequency groups.

Multiplex telephony and telegraphy is at the present time practiced in connection with electro-magnetic waves or oscillations of high frequency guided by wires, in which different high frequencies are used as carriers for different messages, with selective apparatus to select the different carriers or carrier waves and for reducing them to audibility at the receiving station. By this method a different message for each frequency may be transmitted when the frequencies vary from each other in a proper degree.

With my improved method of multiplex telegraphy, I am able to employ electro-magnetic waves or oscillations of a single high frequency for transmitting several different messages so that the number of messages which may be safely transmitted by a single conductor or circuit without interference under the present practice may be multiplied as many times as the number of messages which can be impressed upon and transmitted by the electro-magnetic waves or oscillations of one frequency can be successfully applied.

As pointed out in my pending application No. 445,968 I have found it practicable to mechanically tune a receiving apparatus such as a movable coil so that it will respond to and vibrate with certain current frequencies and will not respond to other frequencies. Just within what range it is possible to effect this mechanically tuning has not as yet been determined, but I have demonstrated that it is practicable to effect this mechanically tuning with a range of from

80 to 300 cycles or vibrations and within this range to secure eight different periods at which reception can take place without interference. In other words, by starting at 80 cycles or vibrations per second and varying the periods by 20 cycles, I secure 12 periods between 80 and 300, differing from each other by 20 cycles or vibrations per second at which these mechanically tuned receiving devices will respond to their respective periods or vibrations and not respond to the other periods or vibrations.

Under these conditions it will be readily apparent that one electro-magnetic wave frequency of say 20,000 cycles per second can be made to transmit 12 different messages when the oscillations at this frequency are broken up into 12 different groups, each group of which will differ from the other groups by 20 or more frequencies or interruptions per second and inasmuch as it is possible to employ high frequency waves which differ from each other by a comparatively small percent without interference, the number of messages which may be transmitted over a single conductor or circuit, it will be seen, is limited only by the number of different electro-magnetic wave frequencies which could be employed or in practical application by the amount of space necessary to equip the proper transmitting and receiving stations. Under some conditions I have found it desirable to employ an auxiliary circuit for the receiving apparatus which may be electrically tuned to the low frequency groups to operate the receivers.

In the drawings which form a part of this specification:

Fig. 1 is a diagrammatic view illustrating a simple plan for carrying out my improved method of telegraphy in which four transmitting stations and four receiving stations are applied to the same circuit, these stations being shown in pairs with one high frequency for each pair and a different interrupted or group frequency for each station of each pair, the receiving stations being similarly arranged.

In Fig. 2 I have illustrated in diagrammatic form circuits and apparatus for transmitting four messages in each direction over a single conductor. In this case four different high frequencies are indicated and two different group frequencies, that is, one

group frequency for messages transmitted in one direction and another group frequency for messages in the other direction.

Fig. 3 is a diagrammatic view showing 5 modifications of the sending and receiving devices.

In carrying out my invention I make use of any well known apparatus now to be obtained for producing the necessary high frequency electro-magnetic waves or oscillations and as such devices are now in common use and on the market, I have not attempted to show them. These high frequency waves or oscillations will be applied 10 to the circuit in any desired way preferably in the manner as now applied to wireless circuits which circuit may be tuned in resonancy therewith in the usual way. For each of the high frequency circuits thus employed I insert at the transmitting station 15 as many circuit breakers as is desired, within the limits of the tuning of the receiving devices, to break up these frequency waves into low frequency groups of the desired period to correspond to the tuning of the receiving devices and upon these group frequencies, I impress the telegraphic signals 20 through any suitable telegraphic transmitter.

30 At the receiving end, I employ any well known method of receiving and securing resonance with the high frequency waves preferably through the vacuum tube detector and in the plate circuit of this receiving agency of a three electrode device. I place my mechanically tuned receiving device 35 preferably in the form of a relay and where such a rectifying detector is used, I interpose between the detector and relay, a transformer in order to secure the necessary current alternations to operate the tuned vibrating receiving device. When this tuned 40 vibrating receiving device is a relay it may be arranged to control a local circuit operating 45 an ordinary sounder or any other suitable translating device.

Referring to Fig. 1 of the drawings at the left end of the sheet is shown a transmitting station A and at the right end a receiving station B. The transmitting station is arranged to transmit and the receiving station is arranged to receive four different messages at the same time. For the purpose of illustration I have shown two of the sending 50 circuits operating with one high frequency say 20,000 cycles and the other two at another high frequency, say 30,000 cycles. Each of these circuits are provided with an interrupter to break up the high frequency 55 oscillations into groups of a frequency which will correspond to the mechanical tuning of the receiving device. I have indicated in the drawings one of the circuits of 20,000 frequencies interrupted eighty times per 60 second and the other one hundred times per 65

second, the same being true of the circuits using the thirty thousand frequencies. An ordinary telegraph key or other transmitter provided in each circuit for interrupting the circuit by long and short intervals corresponding to dots and dashes. The equipment for supplying high frequency currents may be such as is now well known for supplying these high frequency currents or oscillations in wireless practice. 70

In the drawings the respective circuits are numbered 1, 2, 3, and 4 each of which is provided with the usual variable condenser c^1 , c^2 , c^3 , and c^4 and the variable coil a^1 , a^2 , a^3 , and a^4 . Some form of generator for producing the high frequency currents or oscillations such as g is connected to the primaries p^1 , p^2 , p^3 , and p^4 of transformers, the secondaries s^1 , s^2 , s^3 , and s^4 of which are in the respective circuits 1, 2, 3, and 4 which 80 would correspond to the aerial circuits in a wireless system. The interrupters which break up the high frequency waves or oscillations into groups of the desired frequency as for instance 80 and 100 frequencies per second for the respective circuits are shown 85 at b^1 , b^2 , b^3 , and b^4 . The transmitting devices which may be of any desired type for transmitting the signals such as dots and dashes in the ordinary Morse code are indicated 90 at d^1 , d^2 , d^3 , and d^4 .

At the receiving station the circuits 5, 6, 7, 8 correspond to the usual aerial circuits of a wireless station each of which is preferably grounded through the usual variable condensers c^5 , c^6 , c^7 and c^8 and connected to the detectors e^1 , e^2 , e^3 and e^4 preferably of the three electrode vacuum tube type, this connection being established in the usual way through coupling coils t^1 , t^2 , t^3 , t^4 . In the plate circuits f^1 , f^2 , f^3 and f^4 of each of these detectors, I insert the primaries of transformers h^1 , h^2 , h^3 and h^4 , the secondary circuit of each of which includes a vibrating coil receiving device r^1 , r^2 , r^3 and r^4 . Each 100 of these receivers are mechanically tuned in the manner explained in my pending application to respond to a given number of vibrations. In the present case the receivers r^1 and r^3 will be tuned to eighty vibrations and the receivers r^2 and r^4 to 100 vibrations to correspond to the transmitting circuits 1, 3 and 2, 4. These receivers may be in the 105 nature of relays or recorders. If recorders, they would preferably be of the siphon type adapted by their vibrations to record long and short intervals of vibration corresponding to the dots and dashes at the transmitters as shown in the pending application above referred to. If used as 110 relays they would be adapted to control a local circuit through which any suitable translating device could be operated. In the drawings I have shown each of 115 these vibrating receiving devices acting 120

as relays by supplying the vibrating coils with tongues k^1 , k^2 , k^3 and k^4 adapted to vibrate between contacts which will make and break circuits j^1 , j^2 , j^3 and j^4 through other relays n^1 , n^2 , n^3 and n^4 which in turn make and break circuits which include the usual sounders or other translating devices m^1 , m^2 , m^3 and m^4 .

In Fig. 2 I have illustrated four transmitting and four receiving circuits at two stations. In this diagram the transmitting mechanism is not shown in detail but is indicated in diagram at the top of the sheet. At that station at the left of the sheet I have indicated four transmitting sets 9, 10, 11, 12 and at the station at the right of the sheet four similar transmitting sets 13, 14, 15 and 16. Each of these sets will be supplied with apparatus similar to that shown at station A in Fig. 1 which will supply the high frequency currents of different cycles each broken up into groups of a desired frequency. In this case I have illustrated the high frequency currents of 20,000, 30,000, 40,000 and 50,000 for the respective circuits. For each of the transmitting stations at the left of the sheet I have indicated group frequencies of 100 and, for those at the right of the sheet group frequencies of 200. The receivers for these various circuits are the same as described with reference to Fig. 1, there being a vacuum tube detector for each of the receiving circuits and a vibrating receiver mechanically tuned to the required frequency; those receivers at the station at the left being tuned to 200 cycles to correspond with the group frequencies of the sending circuits of the stations at the right and those receivers in the station at the right being tuned to 100 cycles to correspond to the group frequencies of the sending stations at the left.

It will be understood in the operation of this system that the incoming circuits for these receiving stations will be electrically tuned in the usual way to the high frequency waves or oscillations which will be impressed upon the respective detectors thus producing unidirectional currents in the plate circuits of the detectors in groups corresponding to the frequency of the interruption at the sending station and that the receiving devices being mechanically tuned to the respective group frequencies will respond to those particular frequencies.

In the lay-out shown in Fig. 2 instead of using high frequency currents of different frequencies for the eight different circuits, that is, four in each direction, I could employ high frequency currents of the same frequencies with interrupters for the different circuits adapted to interrupt these high frequency currents at the low frequencies of say from 80 to 220 or additional circuits could be provided with the same

group frequencies for each of the high frequency currents indicated, that is, instead of the eight circuits herein illustrated (four in each direction) with the same four high frequencies and using group frequencies of 70 from 80 to 220 varying from each other by 20 cycles we could have 32 circuits, in other words, for each high frequency there could be eight different circuits. As the limits within which electric tuning can be established for these high frequency currents is close, it will be seen that the number of circuits which can be impressed upon a single conductor has a very wide range.

Where the high frequency currents such as herein described are used in connection with low frequency groups, multiplex telegraphy can be effected over any of the ordinary circuits now employed for telephonic or telegraphic purposes without disturbing the regular circuits now in use as the high frequencies being above audibility will not interfere with telephonic conversation nor would they interfere with the ordinary battery transmission for telegraphic purposes.

I have found it advantageous in some cases to employ at the receiving end an additional circuit in connection with the detector circuit which will be separately tuned in electrical resonance with the particular low frequency group, that is to be received by that circuit and place the mechanically tuned receiver directly in this circuit. In this case, the usual detector circuit will be tuned to the high frequency waves and the secondary circuit will be tuned to the low frequency groups. This has special advantages where the circuit may be subjected to outside influences, and it has its advantages whether employed in connection with conductors or guide wires with a high frequency current or employed with radio transmission without the use of wires or conductors.

Where this auxiliary tuning is effected for the low frequencies, an ordinary telephone receiver may be substituted for the mechanical tuned device as shown at x in Fig. 3 in which the range of low frequencies is very materially increased since such a receiver will respond to practically all frequencies within the range of audibility.

Having thus described my invention, I claim:

1. In a system of multiplex telegraphy, means at a sending station for supplying current of different high frequencies on different circuits connected to a single conductor and means for producing comparatively low frequency groups of high frequency currents in each of said circuits and impressing upon these groups signals corresponding to dots and dashes in connection with apparatus at a receiving station comprising an electrically tuned device for each

high frequency current in resonance therewith, and a separate receiving device for each group comprising a vibrating coil mechanically tuned to the low frequency groups 5 which receiving devices are connected in multiple to said conductor.

2. The method of transmitting and receiving signals which consists in impressing upon a single conductor different high frequency currents from different circuits, one 10 for each high frequency, varying these high frequency currents into groups of comparatively low frequency and impressing the signals upon the low frequency groups selecting the high frequency currents at a receiving station by vacuum tubes electrically 15 tuned to the respective frequencies and selecting the low frequency groups by vibrating coil receiving devices mechanically 20 tuned to said groups.

3. In a system for multiplex telegraphy, means at a sending station for supplying to a single conductor high frequency currents in comparatively low frequency groups and 25 impressing upon these groups the signals to be transmitted in connection with apparatus at a receiving station comprising vacuum tube detectors, one for each high frequency and in resonance therewith, and a 30 separate receiving device for each group connected in multiple with said detector and comprising a vibrating coil mechanically tuned to the low frequency groups and responding to the signals impressed thereon.

4. In a system of multiplex telegraphy, means for supplying to a single conductor currents of different high frequencies in groups of comparatively low frequency and impressing upon these groups signals to be 35 transmitted, a vacuum tube detector at a receiving station for each different set of signals to be received and adapted to select a particular high frequency, and a secondary circuit including a vibrating coil receiver 40 mechanically tuned to frequencies of a particular group and to translate the signals carried thereby.

5. In a system of multiplex telegraphy, a plurality of sending devices comprising

means for supplying different high frequency currents, and means connected with each of these devices for producing comparatively low frequency groups of high frequency currents, and separate means for impressing on the low frequency groups signals 50 corresponding to dots and dashes and impressing the various low frequency groups of high frequency upon a single conductor, receiving devices comprising vacuum tube detectors in resonance with the high frequency currents and mechanically tuned vibrating coil receiving devices mechanically tuned to the low frequency groups at a receiving station and connected in multiple to said conductor and adapted to respond to 55 the different frequencies and to translate the different signals impressed on said different frequencies.

6. In a system of multiplex telegraphy, the combination at a sending station, means 60 for supplying currents of different high frequencies to different circuits and in each of said circuits for producing comparatively low frequency groups of said high frequency currents and for impressing signals on said 65 low frequency groups in combination with a vacuum tube detector at a receiving station and a transformer in the plate circuit of said tube, a mechanically tuned vibrating coil relay connected to said transformer and 70 a translating device operated by said relay for the purpose set forth.

7. The method of transmitting and receiving signals which consist in impressing upon a single conductor different high frequency 75 currents varying each of these high frequency currents into groups of comparatively low frequency and impressing different signals upon the low frequency groups of each of said high frequencies selecting 80 the different high frequency currents at a receiving station by electrically tuning and selecting the low frequency groups of each high frequency by mechanically tuning.

In testimony whereof, I have hereunto set 85 my hand this 28th day of April, 1921.

WILLIAM M. BRUCE, JR
